UNITED STATES PATENT OFFICE.

HENRY H. ABBOTT, OF COLDWATER, MICHIGAN.

TWO-CYCLE ENGINE.

1,175,107.

Specification of Letters Patent. Patented Mar. 14, 1916.

Application filed November 8, 1913. Serial No. 799,928.

To all whom it may concern:

Be it known that I, HENRY H. ABBOTT, a citizen of the United States, residing at Coldwater, in the county of Branch and State of Michigan, have invented certain new and useful Improvements in Two-Cycle Engines, of which the following is a specification.

My invention relates to that type of internal combustion engines in which a vacuum is developed on the explosion stroke and communicated to the explosion chamber to assist in scavenging at the end of that stroke, and particularly to those embodiments of the principle which use both preliminary and main exhausts.

The object of my invention is to get compression of the entire charge by cutting off both preliminary and main exhausts before the compression stroke; also to avoid waste by delaying intake of new charge until after scavenging has commenced; also to insure pure mixture around igniter by locating the same in an offset chamber at opposite end of piston stroke from exhaust ports; and with these and minor objects in view my invention consists of the parts and combination of parts as will be more fully hereinafter pointed out.

In the drawing:—Figure 1 is a longitudinal section through the cylinder crank case and immediately associated parts of an explosive engine. Fig. 2 is a detail sectional view of the rotary exhaust valve, and its casing, the valve being in elevation. Fig. 3 is a transverse section on the line 3—3, Fig. 2.

The reference numeral 1 designates a cylinder for a two cycle engine which has two interior diameters; that is to say the upper part of cylinder 2 is of less diameter than the lower part 3 of the cylinder.

4 is the crank case.

5 is the inlet pipe.

6 is a piston having two diameters corresponding with the two diameters of the cylinder, the lower portion 7 of the piston constituting the larger diameter thereof.

8 is a crank mounted on a suitable shaft.

9 is a crank pin on which the connecting rod 10 is pivoted, said connecting rod being secured at its upper end as at 11 to the piston.

12 is a plug screwed into the cylinder above the valve 20.

13 is the preliminary exhaust port and 14 is the main or second exhaust port.

15 is an exhaust pipe registering with the exhaust port 13 and provided with a rotary valve 16 having a port 17 adapted to register with the exhaust port 13. It will be noted that the exhaust pipe 15 has a water space 18.

20 is a valve which controls the opening into the chamber 29 and is held on its seat by the spring 21, one end of said spring 65 being seated on a shoulder integral with chamber 30, while the other end is seated on the washer 22, said washer being held in place by the pin 23. 26 is a push rod which is operated by the cam 27 imparting its 70 motion in turn to the valve 20.

28 is a carburetor connected to the chamber 30 by the pipe 5.

25 is an exhaust passage, one end communicating with the enlarged diameter at 75 the lower portion of the cylinder and the other end communicating with the exhaust pipe 15.

24, Fig. 2, is a port in rotary valve 16 which controls the opening into a chamber 80 25.

The operation is as follows: Beginning with the piston 6 at the top of the stroke and a charge of explosive mixture fully compressed, ignition takes place increasing 85 the pressure and forcing the piston down. As the piston nears the lower end of the stroke, the preliminary exhaust port 13 is opened and the gases rush into the exhaust pipe 15 through the rotary valve 16 and 90 its port 17 and reduce the pressure in chamber 2 to about that of atmosphere, the position of port 17 being now such as to permit this; but when the lower edge of the exhaust port 13 has been passed by the piston 6 and before the upper edge of the second exhaust port 14 is passed, the movement of the rotary valve has closed the port 13, so that none of the gases can return into the cylinder. In the meantime, the piston, 100

on its travel downward, has created a vacuum in the enlarged diameter 3 of the cylinder and the instant that the upper edge of the piston has passed the upper edge of the second exhaust port 14, the remaining gases 105 in the cylinder expand into the space 3, thus greatly reducing the residual products of combustion in chamber 2 and creating a partial vacuum therein. The valve 20 is now opened and atmosphere rushes through the 110 carburetor 28, taking up the fuel constituent, then through passage 30, and past

valve 20, into chamber 29 and thence into chamber 2 to relieve the vacuum in the latter, and present the new charge ready for compression. The proportion of burned charge remaining in chamber 2, encountered by incoming new charge, is small, and is even further reduced in volume as it gives off some of its heat to the new fuel mixture. On the up-stroke of the piston, the 10 valve 20 is closed so that the charge in chamber 2 is compressed ready for the next ignition. At the same time, the burned gas in chamber 3 is forced out into chamber 25 and thence into exhaust pipe 15, the port 24 15 in the rotary valve having in the meantime arrived in position to permit this. When the piston 6 has reached the end of the up-stroke, or thereabout, the rotary valve has moved to shut off communication with the 20 chamber 25, and the cycle of movements commencing with ignition, may now be repeated.

Inasmuch as the rotary exhaust valve in its control of port 13 is used only for discharging the burned gases until pressure in the cylinder 2 is lowered down to that of the atmosphere (or slightly below atmosphere if we regard the residual suction effect of the gases speeding through the exhaust passage), it is essential that it should open as late in the expansion stroke as possible and close immediately after the pressure has reached that of the atmosphere, and still give plenty of area to the vacuum ports. 30 My rotary valve does this and is absolutely positive in action, and can be adjustable to give the best results, inasmuch as it is timed in unison with the crank of the engine. The port 24 which remained closed until the end 40 of the downward stroke of the piston and until the spent gases have expanded into the vacuum chamber 3, opens only when the piston starts upward. But since the upward movement of the piston begins to raise the 45 pressure in the chamber 3, as well as in chamber 2, there is no tendency to expel any of the new charge through the ports 14. It will, therefore, be seen that whereas in engines of ordinary construction, less than the 50 entire new charge is compressed owing to the lag or delay in closing the exhaust port, and to the suction produced by the momentum of the exhaust gases still moving rapidly through the exhaust passage at the 55 commencement of the upward stroke, neither of these influences exists in the present construction, for the reason that the primary exhaust port 17 is closed before the intake valve 20 is open and the second exhaust outlet 60 25 is not opened until the return movement of the piston has commenced and pressure consequently begins to rise in the chamber 3. In other words, the use of the rotary valve makes it possible to compress the 65 charge the full length of the stroke, and

as a result none of the explosive mixture is lost.

All of the objectionable features of the crank-case compression type of two cycle engines are eliminated by my invention because I do not employ crank-case compression to force the charge into the cylinders with the resultant loss from leakage through bearings and the like; furthermore, the drawing of the burned charge into the lower 75 enlarged diameter of the cylinder cools the charge considerably, which results in the gas shrinking and thereby eliminates a greater amount of burned gas from the chamber 2.

Backfiring cannot have the same results in an engine constructed according to my invention as in the type of engines heretofore used where the total amount of gas in the crank case is four or five volumes. In my engine, only the gas between the inlet 85 port 29 and the carburetor can back fire and this only occurs when the mixture is lean, and can be easily overcome.

An engine constructed in accordance with this invention, when throttled, has a reduction in pressure of the contents of the cylinder, under the pressure of the atmosphere, amounting to several pounds, which results in more positive introduction of the fuel charge into the cylinder; whereas the crank-case compression type has an increase of pressure in the crank case over the pressure of the cylinder, amounting to only a few ounces, which causes the introduction of the fuel charge into the cylinder to be very uncertain, and results in irregular running and backfiring.

Inasmuch as the charge enters the cylinder at a point about the spark plug and thereby perfectly scavenges this portion of the cylinder, an explosion at every up-stroke of the piston is insured. The present construction will make a very flexible motor, and one that will be of special advantage in driving automobiles, where great flexibility is very important.

What I claim is:—

1. A two-cycle combustion engine having a combustion chamber containing a working piston and provided with a primary exhaust port, a vacuum chamber having a port of communication with the combustion chamber and removing residual burned gases from and developing vacuum in said combustion chamber, a suction fuel-feeding passage opening into the combustion chamber, a mechanically actuated valve for opening and closing the primary exhaust passage near the end of the working stroke; means for opening said port of communication after the primary exhaust passage is closed, and a mechanically actuated valve for opening the fuel-feeding passage, timed to open the same only after communication has been established between the combustion chamber 130

and the vacuum chamber and while vacuum exists in said combustion chamber.

2. A two-cycle combustion engine having a combustion chamber containing a working piston and provided with a primary exhaust port, a vacuum chamber having a port of communication with the combustion chamber and removing residual burned gases from and developing vacuum in said combustion chamber, a suction fuel-feeding passage opening into the combustion chamber, a mechanically actuated valve for opening and closing the primary exhaust passage near the end of the working stroke; means for opening said port of communication after the primary exhaust passage is closed, and a mechanically actuated valve for opening the fuel-feeding passage, timed to open the same only after communication has been established between the combustion chamber and the vacuum chamber and while vacuum exists in said combustion chamber; the working piston being also constructed and adapted to operate in the vacuum chamber for developing the vacuum therein and constituting the means for closing the port of communication between said vacuum chamber and the combustion chamber and timed to effect said closure shortly after the commencement of the compression stroke of the piston, and said piston operating to raise the pressure in the vacuum chamber, with its port-closing movement and thereby preventing flow of fuel mixture through said port of communication as compression commences in the combustion chamber.

3. A two-cycle combustion engine having a combustion chamber containing a working piston and provided with a primary exhaust port, a vacuum chamber having a port of communication with the combustion chamber and removing residual burned gases from and developing vacuum in said combustion chamber, a suction fuel-feeding passage opening into the combustion chamber, a valve for positively opening and closing the primary exhaust passage near the end of the working stroke; means for opening said port of communication after the pri-

mary exhaust passage is closed, and a positively actuated valve for opening the fuel-feeding passage, timed to open the same only after communication has been established between the combustion chamber and the vacuum chamber and while vacuum exists in said combustion chamber; said piston being also adapted to operate in the vacuum chamber for developing vacuum therein and expelling products of combustion therefrom; said vacuum chamber being provided with a discharge port, and the primary exhaust valve being also adapted to control the vacuum chamber exhaust port.

4. In an internal combustion engine, an explosion chamber, a vacuum chamber, a preliminary and a second exhaust passage communicating successively with the explosion chamber, said second exhaust passage being formed in part of the vacuum chamber, and a rotary valve controlling back flow through both exhaust passages.

5. In an internal combustion engine, an explosion chamber, a vacuum chamber, a preliminary and a second exhaust passage communicating successively with the explosion chamber, said second exhaust passage being formed in part by the vacuum chamber, a valve casing forming part of both exhaust passages and a common rotary valve in said casing.

6. In an internal combustion engine, an explosion chamber, a vacuum chamber, a preliminary and a second exhaust passage communicating successively with the explosion chamber, said second exhaust passage being formed in part by the vacuum chamber, a valve casing forming part of both exhaust passages, a rotary valve in said casing common to both of said exhaust passages and having a separate port for each exhaust passage.

The foregoing specification signed at Coldwater, Mich., this 18 day of October, 1913.

HARRY H. ABBOTT.
